W. B. Hutchinson.

UNITED STATES PATENT OFFICE.

HENRY K. C. MAXSON, OF NEW YORK, N. Y.

CLEANING-TOOL.

1,373,141.

Specification of Letters Patent. Patented Mar. 29, 1921.

Application filed May 7, 1920. Serial No. 379,439.

To all whom it may concern:

Be it known that I, HENRY K. C. MAXSON, a citizen of the United States, and a resident of the city, county, and State of New York, have invented a new and useful Improvement in Cleaning-Tools, of which the following is a full, clear, and exact description.

My invention relates to improvements in cleaning tools, and the object of my invention is to produce a simple, practical and inexpensive tool which can be used to advantage in scraping and cleaning the inner ends of spark plugs so as to remove carbon or other materials therefrom, and the tool is to this end provided with a handle, and with blades extending from the opposite ends thereof, one of the blades being provided with a hook-shaped scraping end, and the other with a sharpened end projection, and both being preferably narrow so that they can be readily inserted in the hollow end of a spark plug. Both the blades are made of flat metal, preferably tempered steel, so that hard carbon or other matter which adheres closely to the plug can be removed readily, and one or both of the blades serves as a gage, and to this end is made of a width for at least part of its length corresponding to the width of the proper gap between the electrodes of the plug, so that by adjusting the points of the electrodes in such a way that the distance between them will correspond to the gage represented by the width of the blade, a gap of right width is had. While the tool is particularly adapted, as will hereinafter appear, for cleaning spark plugs, and while this is its principal use, it is obvious that it can be used for very many other analogous purposes. In carrying out the invention the blades can advantageously be made in one piece extending through the handle and projecting from the ends, as will herein-
after appear.

Reference is to be had to the accompanying drawings forming a part of this specification, in which similar reference characters indicate corresponding parts in all the views.

Figure 1 is a side elevation of the tool giving an edge view of the blades, and Fig. 2 is a plan view of the tool.

The tool is provided with a handle 5 which can be of any desired design and of any suitable material, and extending from

the ends of the handle are thin blades 6 and 7, the former being bent at an angle to its plane at the end as shown at 8, and the end edge is sharpened so that the hook thus formed can be used to advantage in scraping the surface of a spark plug, or other surface to be cleaned of closely adhering material. The other blade 7 is cut as shown at 9 at its edge, at an inclination of the axis of the blade, so that a narrow pointed edge is produced which can be used to advantage in punching material loose or in other work of cleaning.

The blades 6 and 7 can be advantageously made in one piece so as to extend through the handle 5 which can be attached in any convenient way, and in order that the handle may get a better grip upon the metal and hold it more firmly, it is advisable to corrugate a part of the blade material held in the handle, as shown at 5^a in Fig. 1.

At least one of the blades should be made of a thickness corresponding to the desired width of the spark gap of the plug, which is usually about 25/1000 of an inch, so that the electrode points when spaced the width of the blade will be the desired distance for a proper gap.

From the foregoing description it will be seen that I thus produce a very simple and inexpensive tool which is compact, easily carried about, and well adapted to its intended purpose.

Attention is called to the fact that the handle 5 should be made of suitable insulating material so that in working around electric conductors the operator would not get a shock.

I claim:

1. A tool of the kind described comprising an insulating handle, and scraping blades projecting from the opposite ends of the handle, one of said blades having a scraping edge at the end thereof inclined to the length of the blade, and the other blade being bent at an angle to the plane of the blade to form a scraping hook.

2. As an improved article of manufacture, a cleaning tool comprising an insulating handle, and a thin, flat, flexible steel blade extending longitudinally through the handle and projecting from the ends, one blade terminating in a hook shaped scraper, and the other in an inclined scraping edge.

3. A tool of the kind described comprising an insulating handle, and a strip of flexi-

ble metal extending through the handle and projecting from each of the ends thereof to form blades, the ends of said blades being formed into scrapers.

5. 4. A tool of the kind described comprising an insulating handle, and a strip of flat flexible metal extending through the handle and projecting from each of the ends thereof

to form scraping blades, the strip of metal being corrugated for a part of its length 10 lying within the handle.

HENRY K. C. MAXSON.
